UNITED STATES PATENT OFFICE.

OSCAR MARSCHUETZ, OF LOUISVILLE, KENTUCKY.

DESIGN FOR A BATH-TUB.

SPECIFICATION forming part of Design No. 24,889, dated November 12, 1895.

Application filed July 26, 1895. Serial No. 557,246. Term of patent 7 years.

To all whom it may concern:

Be it known that I, OSCAR MARSCHUETZ, a citizen of the United States, residing at Louisville, in the State of Kentucky, have invented and produced a new and original Design for Bath-Tubs, of which the following is a specification, reference being had to the accompanying drawings, forming a part hereof.

Figure 1 is a perspective view of a bath-tub, showing my design. Fig. 2 is a vertical transverse sectional view through the same.

My invention is a design for bath-tubs, the leading feature of which consists of an angular rim having the contour or curvature shown.

5 A denotes the body of the bath-tub.

B is the rim, which extends continuously around the top edge of the tub. In cross-sec-

tion the rim turns outwardly, as at c, along the line where it springs from the walls of the tub, and said rim then slants or inclines upward and outward from the walls of the tub in substantially-straight lines, as at e. The outer edge of the rim has a pendent lip or flange f.

What I claim is—

25 The design for a bath tub herein shown and described.

In testimony whereof I affix my signature in the presence of two witnesses.

OSCAR MARSCHUETZ.

Witnesses:

R. C. KINKEAD,
JOHN YENAWINE.
